CLAIM

The ornamental design for a hearing aids and charging case set, as shown and described.

DESCRIPTION

FIG. 1 is a top, front and right side perspective view of a hearing aids and charging case set in an open state showing our new design;

FIG. 2 is a top, front and right side perspective view of the hearing aids and charging case set in a closed state;

FIG. 3 is a bottom, rear and left side perspective view of FIG. 2;

FIG. 4 is a front elevational view of FIG. 2;

FIG. 5 is a rear elevational view of FIG. 2;

FIG. 6 is a left side view of FIG. 2;

FIG. 7 is a right side view of FIG. 2;

FIG. 8 is a top plan view of FIG. 2;

FIG. 9 is a bottom plan view of FIG. 2;

FIG. 10 is an enlarged view of portion 10 in FIG. 2;

FIG. 11 is a top, front and right side perspective view of a hearing aid of the hearing aids and charging case set, shown separately for ease of illustration;

FIG. 12 is a bottom, rear and left side perspective view of FIG. 11;

FIG. 13 is a front elevational view of FIG. 11;

FIG. 14 is a rear elevational view of FIG. 11;

FIG. 15 is a left side view of FIG. 11;

FIG. 16 is a right side view of FIG. 11;

FIG. 17 is a top plan view of FIG. 11; and,

FIG. 18 is a bottom plan view of FIG. 11.

The broken lines in the drawings illustrate portions of the hearing aids and charging case set which form no part of the claimed design.
